BOBBIN HOLDER FOR WINDING THREAD
ON FISH FLIESCollier A. Elliott, Pittsburgh, Pa., and Richard N.
Palmer, Wellesley Hills, Mass.

Application September 21, 1948, Serial No. 50,316

5 Claims. (Cl. 242—140)

1

This invention relates to an improved bobbin holder and guide which has general utility in all instances wherein it is necessary to manually wind or otherwise apply threads or the like with a high degree of precision and with a predetermined amount of tension.

An important object of the invention is to provide a novel bobbin holder of relatively small dimensions which can be easily held in the palm of the hand of the user, the thread running through a tubular tip from whence it is wound on the desired member, means also being provided for applying a desired measure of braking action to the bobbin as it rotates, thus applying tension to the line or thread. If it is desired to rather tightly wind the thread around the article, greater braking action is applied to the bobbin, and if the thread is to be wound relatively loosely, the brake is adjusted to apply only a slight braking action.

Another object of the invention is to provide a bobbin holder of this character wherein means are provided for intermittently rewinding short sections of the thread back upon the bobbin as the winding operation proceeds.

Without limiting any of the numerous uses to which the device of the present invention may be put, it may be pointed out that an important use of the bobbin holder is in connection with the winding or tying of artificial flies for fishing purposes. This is generally a manual operation requiring a high degree of skill and precise application of the thread to the shank of the hook. It can also be used to form loops in the ends of flylines in order to make it easier to attach the leaders. It is also useful in winding split bamboo rods and in wrapping guides onto any type of fishing rod.

The device of the present invention enables the user to tie flies with far greater accuracy than previous bobbin holders, the fly has a more neat and finished appearance, and the operation is achieved in a minimum length of time.

Another object of the invention is the provision of a novel bobbin holder comprising a barrel, a sleeve, and a tip for the thread, all mounted in axial alignment by threaded connecting means and arranged to be quickly taken apart for cleaning or substitution of parts and reassembled. This arrangement is particularly useful since it permits of quick interchange of bobbins, each carrying different colors and sizes of thread. It also permits interchange of tips of different sizes and shapes. Easy removal of the tip allows it to be cleaned and wax removed in case waxed

2

threads are used. The tip, being the most fragile element, is also easily replaced when broken.

Yet a further object of the invention is to provide a device of this character having novel braking means for applying greater or less tension to the line or thread, the adjustment being quickly effected and without the use of tools. Also important is the fact that adjustment may be accomplished during the winding operation and without removing the bobbin holder from the hand in which it is held.

Another object of the invention is to provide a novel bobbin holder which is compact, light in weight and which is provided with a flat base to permit the holder to be placed on a flat surface during the winding operation while retaining the tension on the thread.

In the drawing:

Fig. 1 is a front elevation of a bobbin holder embodying the present invention.

Fig. 2 is a side elevation thereof.

Fig. 3 is an exploded view, certain parts being in elevation and others being in section.

The device includes a barrel 10, a sleeve 11, a tip 12 and a bobbin 13 journaled for rotation in the barrel. The barrel is formed with a generally rectangular slot 14 extending upwardly from its lower end and which receives the bobbin 13. Bearing means for the bobbin may comprise a pin 15 formed at one end with a transverse slot 16 arranged to receive a screw driver or coin and having a reduced threaded portion 17 at its opposite end. If the screw driver slot is used the pin is so proportioned as to length as to be flush with the curved walls of the barrel when in place as shown in Fig. 1. If desired, this slot may be replaced by a knurled head which extends beyond such walls for manual rotation without the use of a coin or other tool. This latter arrangement has the advantage that the projecting head prevents rotation when the holder is placed on a flat surface.

The bobbin 13 is formed with opposed flanges 23 and 24, the latter having a knurled outer periphery as shown at 25. The side wall adjacent the lower end of the barrel is formed with a concave recess 26 which allows a finger or the thumb of the user to contact the knurled surface 25 of the flange. If the winder is being used by a left-handed person the bobbin may be reversed in order to position the knurled edge conveniently to the user.

The upper section of the barrel is tapered as shown at 27 to fit the contour of the hand. This upper section is further provided with a longi-

tudinal, threaded bore 31 which receives the lower threaded shank 32 of sleeve 11. The upper end of the barrel is also formed with an enlarged circular opening 33 arranged to receive the lower end of the main body position of sleeve 11. On each side of bore 31 are smaller bores 34 which are smooth and which communicate at their lower ends with slot 14. In one of such slots, i.e., the one adjacent smooth flange 23 of the bobbin, there is disposed the braking means which may comprise plural pins 35 and 36 which are held in spaced relation by compression spring 37. The combined lengths of pins 35 and 36 and spring 37 when relieved of compression is greater than the length of either slot 34. Thus, when the bobbin is mounted in slot 14 for rotation on pin 15 the lower end of pin 35 contacts flange 23. Compression of the spring, and therefore braking action, is achieved by contact of lower wall 41 of sleeve 11 with the upper terminal of pin 36. The pressure of pin 35 on flange 23 is thus variable. The bobbin holder is normally held in the right hand and during the winding operation the braking action may be varied by rotating sleeve 11 with the left or right hand.

Sleeve 11 is knurled as shown at 42 and such sleeve is further formed with a longitudinal end-to-end bore 43 which extends through upper shank portion 44. At its upper end the bore is threaded as at 45 and received lower threaded section 46 of tip 12. This tip is of small diameter and has a longitudinal bore 50 of a diameter only slightly larger than that of thread 51 carried on the bobbin. By making this bore sufficiently small sidewise movement of the thread during the winding operation is largely eliminated. The tip is knurled at 52 to facilitate assembly. Both ends of the bore in the tip and the lower end of the bore in the sleeve are bell-mouthed to prevent sharp edges of the metal from injuring the thread. The lower end of the barrel is flat as shown at 54 in order to permit the holder to be placed upright on a flat surface during the winding operation while maintaining tension on the thread.

The sleeve 11 need not be removed from the barrel except when it is necessary to move pins 35 and 36 from one bore to another. The thread 51 carried on the bobbin is first passed through bore 43 in the sleeve, the tip 12 having been removed. The thread may now be threaded through the tip and the latter mounted on the sleeve. Tension of the braking means may now be adjusted to suit conditions. The diameter of the tip being small, it will readily be guided around the delicate portions of the feather which is being attached to the hook and greater or less tension on the thread can be readily achieved by revolving sleeve 11 to barrel 10.

When the bobbin holder of the present invention is used in the tying of fish flies, the hook is held at the bend or at the point in a small vise. A few turns of silk are whipped around the shank, starting where the curve begins to straighten out and working towards the eye. Tension may now be increased by rotating the sleeve. Some increase in braking action, and therefore in tension, may be achieved by applying pressure of the finger to knurled edge 25. The bobbin may now be hung from the hook or placed upon the table with the thread taut in order to free both hands for applying the feathers. With the feather held in place by one hand, the operator takes up the slack thread with his thumb on the knurl as he picks up the holder and

whips a few windings around the base of the feather. He then makes a knot which involves pulling out slack and, after the knot is completed, taking it up again. This operation is repeated after each feather is added. This arrangement for taking up slack is very useful in other applications of the bobbin holder.

It will be seen from the foregoing that the bobbin holder of the present invention is compact and light in weight, that it enables the thread to be applied with a high order of accuracy, and that the task is accomplished with a minimum of fatigue.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What we claim is:

1. A bobbin holder and thread guide comprising a barrel, a sleeve and a tip with detachable connecting means therebetween for mounting the same in axial alignment, such members having a continuous bore extending therethrough for the thread, a bobbin, the barrel having a slot in which the bobbin is mounted for rotation, the section of the bore in the tip being of smaller diameter than the remaining sections of the bore, the barrel having a second longitudinal bore communicating at its lower end with said slot, a pin disposed in said bore, and variable elastic means for urging the pin against the bobbin to exert a braking action thereon.

2. A bobbin holder and thread guide comprising a barrel, a sleeve, and a tip of relatively small diameter, means for detachably mounting the members in axial alignment comprising interengaging threads, such members having a continuous bore extending therethrough for the thread, a bobbin provided with opposed annular flanges, the barrel being provided with means for mounting the bobbin for rotation, the barrel having a second longitudinal bore communicating at its lower end with said slot, a pin and a compression spring disposed in said bore, the pin being arranged to engage one of the flanges of the bobbin to exert a braking action on the bobbin, movement of the sleeve toward and away from the barrel by rotating one member relative to the other varying the action of the spring on the pin.

3. A bobbin holder and thread guide comprising a barrel, a sleeve and a tip with threaded connecting means therebetween for mounting the same in axial alignment, such members having a continuous bore extending therethrough for the thread, a bobbin provided with opposed annular flanges, the barrel having a slot at its lower end in which the bobbin is mounted for rotation, the barrel having a second longitudinal bore communicating at its lower end with said slot, spaced pins and a compression spring therebetween disposed in said bore, the lower pin being arranged to engage one of the flanges of the bobbin to exert a braking action thereon, the upper pin being engaged by the sleeve to exert a predetermined pressure thereon as the sleeve is moved longitudinally relative to the barrel.

4. A thread guide and holder for winding fish.

ing flies and the like, and comprising a barrel, a sleeve and a tip with threaded connecting means therebetween for mounting the same in axial alignment, such members having a continuous bore extending therethrough for the thread, a bobbin provided with opposed flanges, one of which has a knurled periphery, the barrel having a slot at its lower end in which the bobbin is mounted for rotation, such lower end being substantially flat, the barrel having plural, eccentrically disposed longitudinal bores communicating at their lower end with said slot, spaced pins and a compression spring therebetween arranged to be disposed in one or the other of said bores, the lower pin being arranged to engage the non-knurled flange of the bobbin to exert a braking action thereon, the upper pin being engaged by the sleeve to exert a predetermined pressure thereon as the sleeve is moved longitudinally relative to the barrel by rotation of the threaded connection therebetween, the barrel having a recess adjacent the bobbin to permit manual rotation of the bobbin by the finger of the user.

5. A bobbin holder and thread guide for winding fishing flies and the like comprising a barrel, a sleeve and a tip with threaded connecting means therebetween for mounting the same in axial alignment, such members having a continuous bore extending therethrough for the

thread, a bobbin having opposed flanges, the barrel having a slot in which the bobbin is received, and a removable bearing pin upon which the bobbin is mounted for rotation, the barrel having a second longitudinal bore communicating at its lower end with said slot, a pin disposed in said bore, and variable elastic means for urging the pin against a flange of the bobbin to exert a braking action thereon, the barrel having a side-wall recess adjacent the bobbin to permit manual rotation of the bobbin by the finger of the user.
